(57) CLAIM

The ornamental design for a portable and foldable enclosure for toddlers and infants, as shown and described.

DESCRIPTION

FIG. 1 is a perspective view of a portable and foldable enclosure for toddlers and infants, showing our new design; FIG. 2 is a front view thereof;

FIG. 3 is a rear view thereof;

FIG. 4 is a top view thereof;

FIG. 5 is a bottom view thereof;

FIG. 6 is a right-side view thereof; and,

FIG. 7 is a left-side view thereof.

The broken lines shown in the drawings illustrate portions of the portable and foldable enclosure for toddlers and infants that form no part of the claimed design.

1 Claim, 7 Drawing Sheets
